DESIGN FOR A TABLE LAMP

Charles O. Larson, Sterling, Ill.

Application November 28, 1945, Serial No. 124,132

Term of patent 14 years

(Cl. D48—20)

To all whom it may concern:

Be it known that I, Charles O. Larson, a citizen of the United States, residing at Sterling, Whiteside County, Illinois, have invented a new, original, and ornamental Design for a Table Lamp, of which the following is a specification, reference being made to the accompanying drawing, forming a part thereof.

The figure is a perspective view of a table lamp showing my new design. The dominant features of my design reside in the portions shown in full lines.

I claim:

The ornamental design for a table lamp, substantially as shown and described.

CHARLES O. LARSON.
